(57) **CLAIM**

The ornamental design for a sheet having embedded LED lights, as shown and described.

DESCRIPTION

FIG. 1 is a perspective view of the sheet having embedded LED lights of the present invention;

FIG. 2 is a front view of the sheet having embedded LED lights shown in FIG. 1;

FIG. 3 is a left side view of the sheet having embedded LED lights shown in FIG. 1;

FIG. 4 is a right side view of the sheet having embedded LED lights shown in FIG. 1;

FIG. 5 is a top end view of the sheet having embedded LED lights shown in FIG. 1; and,

FIG. 6 is a bottom end view of the sheet having embedded LED lights shown in FIG. 1.

The broken lines shown in the drawings depict portions of the sheet having embedded LED lights that form no part of the claimed design. The sheet having embedded LED lights is shown with a symbolic break in its length. The appearance of any portion of the article beyond the break lines forms no part of the claimed design.
